(57) **CLAIM**

The ornamental design for the armchair, as shown and described.

DESCRIPTION

FIG. 1 is a perspective view of the left, top, and front sides of the armchair of our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a back view thereof; and,

FIG. 8 is a perspective view of the left, top, and front sides of the armchair in a reclined position of our new design.

The broken lines shown in the drawings represent portions of the armchair that form no part of the claimed design.
